(57) **CLAIM**

The ornamental design for a wood-type golf club head with
configured crown and sole, as shown and described.

DESCRIPTION

FIG. 1 is a bottom plan view of a wood type golf club head
showing our inventive design;

FIG. 2 is a side view of a wood type golf club head of FIG.
1 showing our inventive design;

FIG. 3 is a side view of a wood type golf club head of FIG.
1 showing our inventive design;

FIG. 4 is a rear view of a wood type golf club head of FIG.
1 showing our inventive design;

FIG. 5 is a top view of a wood type golf club head of FIG.
1 showing our inventive design;

FIG. 6 is a front view of a wood type golf club head of FIG.
1 showing our inventive design; and,

FIG. 7 is a rear perspective view of a wood type golf club
head of FIG. 1 showing our inventive design.
